(57) CLAIM

The ornamental design for an “abdomen fitness apparatus,” as shown and described.

DESCRIPTION

FIG. 1 is a front, top and left side perspective view of an abdomen fitness apparatus showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, top and left side perspective view of a second embodiment of an abdomen fitness apparatus showing my new design;

FIG. 8 is a front elevational view thereof;

FIG. 9 is a left side elevational view thereof;

FIG. 10 is a right side elevational view thereof;

FIG. 11 is a top plan view thereof; and,

FIG. 12 is a bottom plan view thereof.
